DESIGN FOR A JEWELRY FINDING

Joseph Kantor, New York, N. Y.

Application December 23, 1941, Serial No. 104,804

Term of patent 3½ years

To all whom it may concern:

Be it known that I, Joseph Kantor, a citizen of the United States of America, residing in New York city, county of New York, and State of New York, have invented a new, original, and ornamental Design for a Jewelry Finding, of which the following is a specification, reference being had to the accompanying drawing, forming part thereof.

Fig. 1 is a plan of a jewelry finding showing my new design.

Fig. 2 is an edge view thereof.

I claim:

The ornamental design for a jewelry finding, substantially as shown.

JOSEPH KANTOR.
